UNITED STATES PATENT OFFICE.

GEORGE L. HOLTON, OF UTICA, NEW YORK.

QUICK-BREAK ELECTRIC SWITCH.

SPECIFICATION forming part of Letters Patent No. 636,804, dated November 14, 1899.

Application filed March 25, 1899; Serial No. 710,406. (No model.)

To all whom it may concern:

Be it known that I, GEORGE L. HOLTON, a citizen of the United States, residing at Utica, in the county of Oneida and State of New York, have invented certain new and useful Improvements in Quick-Break Electric Switches, of which the following is a specification.

This invention relates to quick-break electric switches; and the object of my invention is to provide a simple but efficient switch of the character described and in which the conducting-blades will be firmly held in position when the circuit is closed. I attain this object in the construction illustrated in the accompanying drawings, in which—

Figure 1 is an elevated top view of the invention. Fig. 2 is a longitudinal section through line X X, Fig. 1. Fig. 3 is a fragmental elevated side view of the switch.

Similar letters refer to similar parts throughout the several views.

A represents a non-conducting base-plate, to which are secured two terminals B and C, the forward terminal B being provided with a stop B' and on its rear edge with a recess B², with which a locking-plate, hereinafter referred to, engages. Pivotal secured to the rear terminal C are two pair of conducting-blades, forming one pair of main blades D and one pair of snap-blades E, the snap-blades being located inside the main blades and adapted to normally be in contact with the two terminals. The main blades are united at their forward ends by means of an insulating-block D², to which is secured a handle D³. The main blades are further provided with a bolt D⁴, which engages a stop E', secured in the insulating-block E², which unites the forward ends of the snap-blades.

F represents a locking plate or latch which is slidably mounted in two longitudinal slots E³, cut in the sides of the snap-blades. Engaging said latch is a lever G, having a slot G' in its upper end portion and a bearing G² at its lower end. This lever is movably connected with the snap-blades by means of two pair of connecting-arms H' and H², each pair of which are located between the main and snap blades and pivotally connected at their rear ends to the snap-blades by means of rivets I' and I², the forward or free ends of the arms being connected with the lever by means of

pins J' and J², one of which extends across the upper edges of the blades and engaging the slotted portion of the lever, the other pin 55 extending across the lower edges of the blades and engaging the lower bearing in the lever. These pins are connected with each other by means of spring-coils K' and K², which are secured to the pins outside the main blades. 60

The operation of the switch is as follows: Whenever it is desired to break the circuit, the main blades are raised by means of the handle, and by so doing will cause the lever to be drawn back by means of the connecting-arms H' and the upper pin J', which is pushed upwardly through the slot in the lever. The movement of the lever is communicated to the latch, which will thus be drawn back and entirely disengage the recess in the forward terminal when the main blade has been raised to the position indicated by dotted lines in Fig. 2. The friction between the forward terminal and the snap-blades causes the snap-blades to lag behind for some distance 75 from the main blades until the snap-blades reach the extreme upper edge of the terminal, at which point they will be quickly drawn to join the main blades by means of the spiral springs. A quick break in the circuit is thus 80 effected. When the circuit is to be closed, the snap-blades are forced down over the forward terminal by the bolt D⁴, which engages the stud or stop E', which is secured at the forward end portion of the snap-blades. 85 The rounded rear corner of the terminal permits the latch to be crowded back and engage the rear edge of the terminal until it reaches the recess in the said terminal, when it snaps forward and locks the snap-blade in position. 90

I do not desire to limit myself to the particular construction herein shown and described, as various changes may be made therein without departing from the spirit and scope of my invention.

Having thus described my invention, what I claim as new, and desire to secure by Letters Patent, is—

1. In an electric switch, the combination with one forward and one rear terminal, one pair of main and one pair of snap blades pivotally secured to the rear terminal, the snap-blades being located inside the main blades and adapted to normally be in contact with

- the terminals, a locking plate or latch slidably mounted in the snap-blades and adapted to normally engage a recess formed in the rear side of the forward terminal, a lever having a slot in its upper end portion and a bearing in its lower end portion engaging said latch two pair of connecting-arms located between the snap and main blades and pivotally secured at their rear end to the snap-blades, and at their forward ends connected with the lever by means of pins, one of which extends across the upper edges of the blades and engaging the slotted portion of the lever, the other pin extending across the lower edges of the blades and engaging the lower bearing of the lever, two spring-coils connecting the ends of the said pins outside the main blades, substantially as described and for the purpose set forth.
2. In an electric switch, the combination with the terminals, one pair of main blades and one pair of snap-blades pivotally mounted to one of the terminals, the snap-blades being located inside the main blades and adapted to normally be in contact with the terminals, a locking plate or latch slidably mounted in the snap-blades and adapted to normally engage a stop located in one of the terminals, a lever having a slot in one of its end portions and a bearing in its other end

portion engaging said latch, two pair of connecting-arms pivotally secured at one of their ends to the snap-blades, the other ends of said connecting-arms being connected with the lever by means of two pins which extend across opposite edges of the blades and engage respectively the bearing and slot in the lever, the end portions of said pins being connected by intermediate yielding couplings, substantially as described. 35

3. In an electric switch the combination with the terminals, of pivoted main and snap blades adapted to engage said terminals, a locking plate or latch slidably mounted in the snap-blade and adapted to normally engage a stop in one of the terminals, a lever engaging said latch, connecting-arms pivotally secured at one of their ends to the snap-blade, the other ends of said arms being connected with the lever by means of two pins 40 which extend across opposite edges of the blades and engage respectively bearings formed in the lever said pins being connected with each other by means of intermediate yielding couplings, substantially as described. 45
